UNITED STATES PATENT OFFICE.

BERTRAM SHAW, OF BRIGHTON, ENGLAND.

BOOK REST.

Application filed October 5, 1927, Serial No. 224,224, and in Great Britain June 10, 1926.

This invention relates to book-rests of the type which comprise an elongated support adapted to rest upon and to bridge the arms of a chair and a book-support hinged to 5 said elongated support.

The object of the present invention is to provide an improved book-rest of this type, which, when not in use, may be folded up so as to occupy a minimum of space.

10 The present invention consists of a book-rest of the type specified wherein the elongated support is in three portions hinged together so as to be capable of being folded.

In the preferred arrangement the three 15 portions are of equal length and the book-support is hinged to one longitudinal edge of the middle portion, the lateral width of the book-rest being such that when folded it does not extend beyond the ends of such 20 middle portion.

In order that the invention may be clearly understood such an embodiment of the same will now be described by aid of the accompanying drawings in which:—

25 Fig. 1 is a perspective view showing the book-rest in the open position.

Fig. 2 is a similar view showing the book-rest closed.

The book-rest illustrated comprises a 30 frame composed of three portions, *a*, *b* and *c*, the two outer portions *a*, *b*, being connected by the inner edges to the outer edges of the middle portion *c* by means of hinges, *d*.

The connection between the three portions 35 of the frame is such that the two outer portions are folded over in alternation flat against the under surface of the middle portion. For this purpose distance pieces are provided between the two members of one 40 of the hinges and the surfaces of the respective portions to which such members are attached. This results in one of the portions being spaced from the middle portion when folded a distance equal to the thickness of 45 the remaining portion.

In the example illustrated the three portions comprising the frame are of substantially equal length so that they fold into a space equal to the length of the middle portion.

50 When in the extended position the inner edges of the outer portions abut against the adjacent outer edges of the middle portion so as to form a rigid frame having a flat upper surface of such a length as to be capable of straddling the arms of an arm-chair,

and of such a width as to act as the sole support for a book support *e* which is hinged as at *f* by its bottom edge to the top surface of the middle portion *b* of the frame adjacent 60 the rear longitudinal edge of such middle portion.

By this means the support *e* is capable of being turned from a position where it lies flat against the upper surface of the middle 65 portion *b* to an inclined position as indicated in Fig. 1. In this latter position it is supported by a member *g* which is hinged as at *h* to the back of the support *e* its bottom edge, which may be bevelled off, engaging one or 70 other of the longitudinal and parallel grooves *i* cut in the top face of the middle portion *b* as shown in Fig. 1.

In the present example the width of the support *e* is the same as the length of the 75 middle portion *c* of the frame so that the whole structure may be collapsed or folded so as to have an overall length equivalent to the length of the middle portion *c* of the frame.

80 A ledge *j* is provided along the bottom longitudinal edge of the support *e* to hold a positioned book.

I claim—

1. In a device of the class described comprising an elongated support composed of three portions of equal length, the two outer portions being hinged to the edges of the middle portion so that each outer portion is capable of being folded inwards against 90 the middle portion to an out of use position and turned outwards to form a rigid flat support of such length as to permit the same, when so extended to straddle the arms of an arm chair, a book-rest hinged to one 95 longitudinal edge of the middle portion of the elongated support so as to be angularly movable relative thereto and means for supporting the book-rest in one or more angular positions, the lateral width of the book-rest 100 being such that when folded it does not extend beyond the ends of the middle portion of the elongated support.

2. In a device of the class described comprising a support composed of a middle portion and two end portions hinged together and capable of being folded, a book-rest of the same width as the middle portion hinged to the edge of said middle portion, and means for supporting the book-rest in one or 110 more positions.

3. In a device of the class described com-

prising a support composed of a middle portion and two end portions hinged together and capable of being folded, a book-rest of the same width as the middle portion hinged to the middle section at right angles to the way the said end portions are hinged, and means for supporting the book-rest in one or more positions.

4. In a device of the class described comprising a support composed of a middle portion and two end portions hinged together and capable of being folded, a book-rest of the said width as the middle portion hinged to the edge of the middle portion and adapted to be folded over said portion at right angles to the folds of the said support, and means for supporting the book-rest in one or more positions.

5. In a device of the class described comprising a book-rest composed of a middle portion and two end portions hinged together and capable of being folded, a book-

rest of the same width as the middle portion hinged to the middle portion at right angles to the hinges of said support, and means for supporting the book-rest in one or more positions.

6. In a book holder, means for supporting a book-rest on the arms of a chair, said means comprising two outer base members hinged to opposite edges of a middle base member, the book-rest being hinged to an edge of the middle base member, means angularly adjusting the book-rest to the middle base member and lying between the book-rest and said middle base member when the book-rest is folded, and the outer base member folding and parallel to the middle base member, said book-rest and said middle base member being of the same length.

In testimony whereof I affix my signature.

BERTRAM SHAW.
